UNITED STATES PATENT OFFICE.

PHILIP H. LECKINGER, OF ROCHESTER, NEW YORK, ASSIGNOR TO THE HIGH SPEED HAMMER COMPANY, INC., OF ROCHESTER, NEW YORK, A CORPORATION.

DESIGN FOR A DRILL-PRESS FRAME.

55,387.

Specification for Design.

Patented June 1, 1920.

Application filed July 3, 1919. Serial No. 308,657. Term of patent 14 years.

To all whom it may concern:

Be it known that I, PHILIP H. LECKINGER, a citizen of the United States, residing at Rochester, in the county of Monroe and State of New York, have invented a new, original, and ornamental Design for Drill-Press Frames, of which the following is a specification, reference being had to the accompanying drawing, forming part thereof.

The figure is a perspective view of a drill press frame showing my new design.

I claim:

The ornamental design for a drill press frame as shown.

PHILIP H. LECKINGER.
